UNITED STATES PATENT OFFICE.

MOSES E. NEWELL, OF EDWARDSVILLE, ILLINOIS.

AUTOMOBILE HEADLIGHT DIMMER.

Application filed March 12, 1924. Serial No. 698,682.

To all whom it may concern:

Be it known that MOSES E. NEWELL, a citizen of the United States, residing at Edwardsville, in the county of Madison and State of Illinois, has invented certain new and useful Improvements in Automobile Headlight Dimmers, of which the following is a specification.

This invention relates to new and useful improvements in automobile head light dimmers.

The primary object of my invention is to provide a mechanism of the character specified that will eliminate the usual head-light glare commonly encountered in passing automobiles on the street or roadway and will, at the same time, give ample or sufficient illumination to the roadway for a distance of 40 to 60 feet so that the driver or operator of the machine which is equipped with my invention can safely proceed and know what obstructions, if any, are in his path. The non-glare effect attained through the use of my dimmer is accomplished by catching the upper rays of light and deflecting them downwardly and forwardly, increasing the road light for some distance and producing a stronger illumination than is derived from the headlight without the dimmer. In this connection, it is pointed out that the usual dimming of the headlights to avoid glare, produces such a weak illumination of the road that it is unsafe for the driver to proceed for any appreciable distance with his lights dimmed.

With the foregoing and other objects in view that will appear as the nature of my invention is better understood, the same consists in the novel features of construction, combination and arrangement of parts illustrated in the drawings and more particularly pointed out in the appended claim.

In the accompanying drawings which are for illustrative purposes only, and are therefore not drawn to scale:

Figure 1 is a plan view, illustrating the application of my invention.

Figure 2 is a front view.

Figure 3 is a side elevation, the dimmer hoods in lowered or operative position.

Figure 4 is a similar view, the dimmer hoods in raised or inoperative position.

The other views are details of various features of my invention.

Referring to the drawings for a more particular description of my invention and in

which drawings, like parts are designated by like reference characters throughout the several views, A designates the headlight casings, B the light bulbs and C the reflectors of the automobile headlights which are of any standard or approved construction.

Hingedly mounted within the headlight casings A to swing in a vertical plane, above and over the light bulbs B, are the dimmer hoods D. When in operative or lowered position the dimmer hoods set directly over the light bulbs and deflect the upper rays of light downwardly and forwardly on the roadway. When in raised or inoperative position, said hoods permit the full unobstructed reflection of the light rays.

The dimmer hoods are carried by opposite ends of the rock shaft E, extending through and journaled in the headlight casings. Said hoods are perfectly secured to the rock shaft by the eyes or loops F fastened to the upper inner corners of the former and encircling or embracing said shaft. The rock shaft aforesaid, is provided intermediate its ends with a crank arm G, to which is connected, as at a, the forward end of an operating rod H, which extends through the radiator shell and the instrument board b of the machine and is provided with a knob c or handle adapted to be grasped by the operator in manipulating the same.

In practice, when the dimmer hoods D are in raised or inoperative position, the knob or handle c of the operating rod H bears against the instrument board and a pull is exerted on said rod to lower the hoods directly over the light bulbs. When the hoods are in operative position, the upper rays of light are directed downwardly on the roadway and the direct rays of light which would ordinarily produce glare and interfere with the driver of an approaching machine, are eliminated.

They are also provided in the top with vertical perforations b, it having been found on experience that some of the light passing through the perforations adds to the strength of the road light ahead.

From the foregoing description, taken in connection with the drawings, it is thought that the construction, operation and advantages of my invention will be readily understood without requiring a more extended explanation.

Various changes in the form, proportions and minor details of construction may be

resorted to without departing from the principle or sacrificing any of the advantages of my invention as defined in the appended claim.

5 Having described my invention, what I claim as new and desire to secure by Letters Patent, is:—

10 A headlight dimmer for automobiles comprising a pair of hollow dimmer hoods provided in their top walls with vertical perforations, said hoods hingedly mounted to swing in a vertical plane within the headlight casings over the light bulbs and adapted to set in horizontal position directly over 15 and entirely encompassing the upper portions of the latter when in lowered or operative position whereby the upper rays of

light will be deflected downwardly on the roadway and means under the control of the operator for raising and lowering the 20 dimmer hoods, said means comprising a transverse rock shaft extending through and journaled in the headlight casings, loops at the upper rear corners of the dimmers embracing the rock shaft, a crank 25 arm extending from the rock shaft and an operating rod connected with said crank arm and extending rearwardly through the radiator shell to within convenient reach of the operator.

30 In testimony whereof he affixes his signature.

MOSES E. NEWELL.
